CLAIM

The ornamental design for air deflector with magnetic holders, as shown and described.

DESCRIPTION

FIG. 1 is an elevational view of an air deflector with magnetic holders showing our new design;

FIG. 2 is an end elevational view of the same taken looking from the right of FIG. 1;

FIG. 3 is an end elevational view of the same taken looking from the left of FIG. 1; and

FIG. 4 is a top plan view taken looking from above FIG. 1.

All portions of the air deflector with the exception of the magnets and adjacent metal plates shown at the lateral ends of the air deflector, the magnets being shown stippled, are made of clear plastic.
